UNITED STATES PATENT OFFICE.

WALTER H. HIMES, OF PITTSBURGH, PENNSYLVANIA, ASSIGNOR TO WESTINGHOUSE ELECTRIC & MANUFACTURING COMPANY, A CORPORATION OF PENNSYLVANIA.

CENTRIFUGAL DRYING MACHINE.

Application filed June 15, 1921. Serial No. 477,753.

To all whom it may concern:

Be it known that I, WALTER H. HIMES, a citizen of the United States, and a resident of Pittsburgh, in the county of Allegheny and State of Pennsylvania, have invented a new and useful Improvement in Centrifugal Drying Machines, of which the following is a specification.

My invention relates to centrifugally operated devices adapted for drying clothes and it has particular relation to decelerating means for use in connection with apparatus of the above indicated character. It pertains to the subject matter of my co-pending application Serial No. 723,478, filed July 1, 1924.

One object of my invention is to provide braking apparatus by means of which it is impossible to decelerate centrifugally operated devices at such rate as to injure the same.

Another object of my invention is to provide a braking device which is automatically released when the centrifugally operated machine ceases to rotate, thus avoiding the possibility of injuring the driving mechanism by attempting to start the machine with the brake in its effective position.

Heretofore, it has been customary, in the construction of high-speed centrifugal apparatus, to provide a decelerating means in which the braking action exerted on the rotatable member is proportional to the force exerted on the brake lever by the operator. An objection to an arrangement of this type, is that, if the operator applies the brake with too much force, the machine, and particularly the braking apparatus thereof, is likely to be injured.

Briefly speaking, my invention consists in providing a device whereby the weight of the centrifugally operated fabric container or basket is raised from the bearing member upon which it rests during the normal operation thereof. During the braking operation, the basket is sustained by the braking member by means of a device which permits raising the basket from its normal position and prevents applying any braking force thereto, except that caused by the weight of the centrifugal member itself.

In the accompanying drawings,

Figure 1 is a cross-sectional view of a centrifugal drying machine constructed in accordance with my invention.

Fig. 2 is a detail view of a portion of the braking device illustrated in Fig. 1, and

Fig. 3 is a detail view illustrating the basket-raising device illustrated in Fig. 1.

In the drawings, I show a stationary frame member 4 provided with a lower bearing-supporting portion 5, an intermediate casing 6 and an upper basket-containing member 7 which is provided with a detachable lid 8. Within the container 7 is disposed a rotatable container or basket 10 having perforated sides and being adapted to receive clothing or other material from which it is desired to separate water.

The container 10 is provided with a bottom portion 11 which, in turn, is mounted upon a vertically disposed shaft 12. The lower portion of the shaft is disposed within a bearing sleeve 13 mounted within a bearing housing 14 which is supported from the portion 5 of the supporting frame 4. The end of the shaft 12 is supported by a thrust-bearing, of any suitable type, here shown as comprising a ball bearing 15 engaging a detachable portion 16 of the bearing housing 14. The bearing sleeve 13 and the housing 14 are both stationary and are loosely mounted upon the supporting member 5 by means of annular members 17 composed of rubber or other suitable resilient material.

Upon the upper portion of the housing 14 is mounted a cylindrical housing 18 which serves to enclose that portion of the shaft 12 intermediate the container 10 and the bearing housing 14. The housing 18 may, if desired, contain an electric motor for driving the shaft 12. As is best shown in Fig. 3, the bearing sleeve 13 is provided, at its upper end, with a flange 20, portions of which are cut away to form inclined surfaces 21 thereon, the purpose of which will be hereinafter described.

Upon the shaft 12, intermediate the basket 10 and the bearing sleeve 13, is mounted a collar member 22 having a relatively wide horizontally disposed face which is provided with a lining 23 of any suitable material having the desired coefficient of friction, such, for example, as a composition comprising a relatively large proportion of cork.

Loosely mounted upon the shaft 12 is a co-operating oscillatable braking collar member 24, the surface 25 of which is adapted to engage the braking surface 23. The

member 24 is provided with diametrically disposed lugs 26 upon each of which is pivotally mounted a roller member 27 by means of a pin or axle 28. The roller members 27 are adapted to lie upon the lowermost portion of the inclined surface 21 of the bearing member 13, previously described, during the normal operation of the machine.

The member 24 is rotated into its braking position by means of an arm 30 which also prevents the rollers 27 from being moved beyond a predetermined position on the incline 21 by means of the engagement between the braking members 22 and 24. The arm 30 projects through a slot 34 in the casing member 18. The arm 30 is moved by means of an arm 31, mounted upon the shaft 32 which is supported by means of the portion 6 of the stationary frame 4. Upon the opposite end of the shaft 32 is mounted a foot lever 33.

When the operator moves the lever 33, the shaft 32 is rotated and the arm 31 is moved into engagement with the arm 30. The arm 30 is moved a relatively short distance only to rotate the member 24, sufficiently to bring the surfaces 25 and 23 into engagement. As the member 22 is also moved in the same direction as the member 24, the engagement between the members 22 and 24 causes the member 24 to be rotated still farther in the same direction, thus raising the weight of the basket from the bearing 15. A pin 35 mounted on the member 6 prevents the foot lever 33 from moving the arm 30 beyond a predetermined position. The end of the slot 34 in the member 18 through which the arm 30 extends, prevents its being rotated beyond a predetermined position by means of its engagement between the surfaces 23 and 25.

After the weight of the basket 10 is raised from the bearing 15, it is supported only by the contact between the braking surfaces 23 and 25 which will stop the rotation of the basket without imposing any undue strains thereon. The frictional engagement between the surfaces 23 and 25 will depend upon the weight of the articles disposed within the basket 10.

From the foregoing description, it will be observed that the arm 30 is prevented from rotating beyond a predetermined position in order that the rollers 27 may be maintained on the inclined surfaces 21 during the braking position. One of the advantages of this particular arrangement is that, as soon as the basket is stopped, the rollers 24 will roll down the inclined surfaces 21 to their original or non-braking position automatically, thus returning the arm 30 to its original position. The arm 31 is returned to its original position by means of a spring or other resilient device when the foot of the operator is removed from the foot lever 33.

The brake will, therefore, be automatically released when the basket ceases rotation, thus eliminating the possibility of injuring the motor by attempting to drive the basket with the brake on.

It will be noted that the arm 30, which is mounted on the member 24, is adapted for oscillation to effect a braking action on the shaft 12 and also for gyration with the shaft 12 about the resilient bearing within the housing 14. The arm 31, however, which actuates the arm 30 is oscillatable but not gyratable. The foot lever 33 is stationary when not moved by the operator. Thus, the gyratable arm 30 is actuated by the non-gyratable arm 31, it being undesirable to mount the foot pedal on the arm 30 because the latter would probably be moving continuously during the braking period when the operator's foot would be in engagement therewith.

While I have shown but one form of my invention, further changes and modifications may be made without departing from the spirit and scope thereof, and I desire, therefore, that only such limitations shall be placed thereupon as are imposed by the prior art or are specifically set forth in the appended claims.

What I claim as my invention is:

1. In combination with a rotatable member, a braking device adapted to sustain said member during the braking period.
2. In combination with a rotatable member, a braking device adapted to sustain said member during the braking period only.
3. In combination with a rotatable member, bearing members provided therefor and a braking device adapted to sustain said member and to remove the weight thereof from said bearing members.
4. In combination with a rotatable member, bearing members provided therefor and a braking device adapted to remove the weight of said member from said bearing members.
5. In combination with a rotatable member, bearing members provided therefor and a braking device adapted to remove the weight of said member from said bearing members and for subsequently restoring said member upon said bearing members.
6. In combination with a rotatable member, a bearing member provided therefor and a braking device adapted to sustain said member during the braking period and for raising said member out of engagement with said bearing member.
7. In combination with a rotatable member, a bearing member provided therefor and a braking device adapted to sustain said member during the braking period and for raising said member out of engagement with said bearing member throughout a predetermined period and for restoring said mem-

ber to its original position when said member ceases rotating.

8. In combination with a member rotatable about a vertical axis, an anti-frictional thrust bearing, an additional bearing member mounted on said shaft and a co-operating bearing surface adapted to be moved into engagement with said additional bearing member and to raise the weight of the 10 rotatable member from said anti-frictional bearing member.

9. In combination with a rotatable member, a stationary support therefor, a braking member mounted on said rotatable member, a co-operating braking member mounted on said support and means for bringing said braking members into engagement comprising a member moving upon an inclined surface, said means being automatically operable to disengage said braking members.

10. In combination with a rotatable member, a stationary support therefor, a braking member mounted on said rotatable member, a co-operating braking member mounted on said support and means for bringing said last mentioned braking member into engagement with said first mentioned braking member comprising a roller member moving upon an inclined surface.

11. In combination with a rotatable member provided with a vertical axis, a stationary support therefor, a thrust bearing for said rotatable member, a collar member mounted on said rotatable member and provided with a substantially horizontal bearing surface, an oscillatable member mounted on said stationary support and provided with a bearing surface adapted to co-operate with said collar member, said oscillatable member being adapted to be moved into engagement with said collar member by means of roller members moving on an inclined plane.

12. In combination with a rotatable member provided with a vertical axis, a stationary support therefor, a thrust bearing for said rotatable member, a collar member mounted on said rotatable member and provided with a substantially horizontal bearing surface, an oscillatable member mounted on said stationary support and provided with a bearing surface adapted to co-operate with said collar member, said oscillatable member having mounted thereon a plurality of roller members, said stationary support being provided with a plurality of inclined portions adapted to co-operate with said roller members to move said oscillatable member into engagement with said collar member.

13. In combination with a rotatable member provided with a vertical axis, a stationary support therefor, a thrust bearing for said rotatable member, a collar member mounted on said rotatable member and pro-

vided with a substantially horizontal bearing surface, an oscillatable member mounted on said stationary support and provided with a bearing surface adapted to co-operate with said collar member, said oscillatable member having mounted thereon a plurality of roller members, said stationary support being provided with a plurality of inclined portions adapted to co-operate with said roller members to move said oscillatable member into engagement with said collar member and a lever adapted to move said oscillatable member to cause said roller members to engage said inclined surfaces.

14. In combination with a rotatable member provided with a vertical axis, a stationary support therefor, a thrust bearing for said rotatable member, a collar member mounted on said rotatable member and provided with a substantially horizontal bearing surface, an oscillatable member mounted on said stationary support and provided with a bearing surface adapted to co-operate with said collar member, said oscillatable member having mounted thereon a plurality of roller members, said stationary support being provided with a plurality of inclined portions adapted to co-operate with said roller members to move said oscillatable member into engagement with said collar member, a lever mounted on said oscillatable member and adapted to move the same to cause said roller members to engage said inclined surfaces and an additional manually operable lever adapted to engage said first mentioned lever to actuate the same.

15. In combination, an oscillatable gyrate member having a lever mounted thereon and separately mounted means adapted to oscillate said lever.

16. In combination, an oscillatable gyrate member having a lever rigidly mounted thereon and an independent oscillatable non-gyrate lever adapted to engage said first mentioned lever only when imparting energy thereto.

17. In a centrifugal machine, the combination of a rotatable member and means operable by the inertia of said member for exercising a braking action on said member.

18. In a centrifugal machine, the combination of a rotatable member, and means actuatable by an operator and operative by reason of the rotation of said member for applying an increasing pressure to said member and thereby retarding said member.

19. In a centrifugal machine, the combination of a rotatable container, a brake member rigid therewith and means for lifting said container and exercising a braking action on said brake member but preventing the braking pressure on said braking

member from exceeding the weight of said container and parts carried thereby.

20. The combination of a rotatable member, braking means adapted to sustain the weight of said member during the braking operation and automatically operable means for discontinuing the operation of said braking means on the stopping of said member and relieving said means of the weight of said member.

21. The combination of a rotatable member, braking means operative on the application throughout a small interval of time

of a small amount of force by an operator to apply a relatively large amount of braking force throughout a relatively large interval of time for retarding the rotation of said member and automatic means to restore said braking means to an inoperative condition after the retardation has progressed to a predetermined degree.

In testimony whereof, I have hereunto subscribed my name this 8th day of June, 1921.

WALTER H. HIMES.
